UNITED STATES PATENT OFFICE.

SAMUEL F. LEAKE, OF PHILADELPHIA, PENNSYLVANIA.

PNEUMATIC DISPATCH-TUBE RECEIVER.

SPECIFICATION forming part of Letters Patent No. 431,701, dated July 8, 1890.

Application filed October 26, 1889. Serial No. 328,248. (No model.)

To all whom it may concern:

Be it known that I, SAMUEL F. LEAKE, a citizen of the United States, residing at Philadelphia, in the county of Philadelphia and 5 State of Pennsylvania, have invented certain new and useful Improvements in Pneumatic Dispatch-Tube Receivers; and I do hereby declare the following to be a full, clear, and exact description of the invention, such as 10 will enable others skilled in the art to which it appertains to make and use the same:

My invention has relation to stopping the 15 travel or movement of a pneumatic dispatch-carrier by causing it to compress air ahead of it in the receiver ends or tubes at the main and sub stations of pneumatic dispatch-tube systems; and it has for its object an apparatus for quickly stopping the carrier in a short 20 length of receiver without producing the concussion usually incident thereto.

My invention accordingly consists of the 25 combinations, constructions, and arrangements of parts, as hereinafter described in the specification, and pointed out in the claims.

Reference is had to the accompanying drawings, wherein—

Figure 1 is a sectional elevation of a receiver end or tube and devices embodying my 30 invention. Fig. 2 is a like view of another form of the same, and Fig. 3 is a cross-section showing the movable section of the receiver through which the carrier is removed from the same.

A represents the receiver-tube which has a 35 hinged folding or movable section a (see more plainly Fig. 3) to admit of removing the carrier from tube A, and if the latter be also used as a transmitter said section a admits of introducing the carrier into tube A, all of 40 which may be constructed and arranged as desired. In the drawings the movable section a is illustrated as being located near the front end of receiver-tube A, and adjacent to said movable section a is an air-cock or vent a², 45 for a purpose hereinafter to be described.

In front of section a on tube A is a pocket or chamber b, in which is located a slide-valve or gate B, having a latch-head b' for engagement with a lock-latch b², suitably pivoted or 50 supported, as desired. This latch b² may be actuated by any suitable means. In the draw-

ings I have shown it controlled by an electro-magnet C in a battery or supply-circuit 1 1, having a fixed and a movable or spring contact terminal c c', respectively, in a side 55 pocket or recess c² in tube A, which movable contact c' is in the path of and is moved by a traveling carrier a' to close the normally-open circuit 1 1. In advance of the gate or valve B in recess D are corresponding fixed and 60 movable terminal contacts d d' of a normally-open battery-circuit 2 2, which contacts d d' are correspondingly operated by the carrier to close circuit 2 2. Near the rear end of tube A is a pipe-connection e, having cock e' with 65 a reservoir E holding a supply of compressed air, and to the stem of cock e' is secured a suitable lever e², one end of which impinges against a pivoted or fulcrumed lever e³, having an adjustable weight e⁴. Lever e³ impinges against a sliding piston e⁵ in a cylinder e⁶, communicating by means of opening e⁷ with the tube A. To lever e² is suitably secured the core or armature f of a solenoid or electro-magnet F, included in circuit 2 2. 75 To one side of tube A is a small pipe G, communicating with the rear end of tube A, as indicated at g, and with the opposite end of tube A, near its removable section a, as shown at g'. 80

Between the reservoir E and valve B, if desired, are two or more other pipe-connections h h', each having two separate valves h² h³, and leading to separate reservoirs H and H', containing supplies of air under different 85 pressure. The valves h² h³ each have stem-levers h⁴ and h⁵, respectively, with adjustable weights, which levers connect, respectively, with suitable pistons h⁶ h⁷ in cylinders h⁸ h⁹, communicating with tube A. The valves h² 90 are normally open, and the valves h³ are normally closed.

As the reservoirs H H', with their pipe-connection h h' and just-described attendant appliances, may or may not be used as desired, 95 I will here premise that I will describe their operation after having first set forth the operation of the other parts, heretofore described, and which is as follows: The gate or valve B is normally raised and in locking engagement with latch b', as indicated in Fig. 1, 100 the valve e' between reservoir E and tube A

is closed, and the levers e^2 and e^3 , together with piston e^5 , are in the position indicated in Fig. 2, and the circuits 1 1 and 2 2 are normally open. As soon as a carrier a' arrives 5 at the gate or valve B it lifts the contact d' (see Fig. 1) to close the circuit 2 2, the solenoid F then acts to move its core f , which in turn opens valve e' in pipe e and causes lever e^2 to depress lever e^3 and plunger e^5 to the position shown in Fig. 1, whereupon the valve 10 e' being open, the compressed air in reservoir E passes into tube A, filling the same. As soon as the carrier meets this air it begins to compress the same, and when the carrier 15 passes the contact c' the circuit 1 1 is closed, making magnet C active to withdraw armature latch or lever b^2 from gate or valve B, which then falls and closes the front end of tube A, as indicated in Fig. 2. The carrier 20 in traveling through tube A continues compressing the air therein to quickly reduce its momentum, until, having reached the point indicated by dotted lines xx , Fig. 2, it stops and does not contact with the rear end of 25 tube A. Long before reaching said point, however, the compression by the carrier of the air under pressure in tube A has been such that such further compression by the carrier causes the piston e^5 to raise and close 30 the cock e' , as indicated in Fig. 2, in order to prevent the compressed air supplied to pipe A being forced back by the carrier into reservoir E. Meanwhile a certain proportion of the air-pressure ahead of the carrier has found 35 its way through pipe G to back of the carrier, so that when the latter comes to a state of rest and the reaction of the compressed air in tube A ahead of the carrier moves it toward the front end of the tube A there is 40 an air-supply behind the carrier for it to compress as it returns to the sectional part a of tube A, and as said carrier slowly returns to said part a the cock a^2 is opened to admit of the escape of air from tube A between the 45 carrier and gate B, so that the carrier will finally come into position opposite the part a , in order that when it is moved to one side the carrier can be withdrawn from tube A. 50 As this is done, the pressure of air in tube A escapes, and after the carrier is removed from tube A the gate or valve B is manually or otherwise lifted, as desired, into engagement with latch b^2 to place all of said parts in their normal positions. It will be noted, therefore, that when the reservoir E is alone used 55 the entire supply of one given pressure of compressed air is admitted to tube A at once, that such admission of air and cutting off of the same is under the control of the traveling 60 carrier in the tube A, and that such admitted air is an addition to the air or pressure normally in tube A. When the reservoirs H H' are used and the pressure of air in reservoir E is less than that in reservoirs H H', the air-pressure in reservoir H being less than the 65 air-pressure in reservoir H', the pressure in the latter of which is the highest of all, the

operation first described for the admission of air from reservoir E is the same as before set forth, except that as soon as the carrier in 70 tube A compresses the air under pressure therein to an extent greater than that exerted by the weighted lever h^4 for valve h^2 for reservoir H, which the carrier does before coming to cylinder h^8 for reservoir H, the piston h^6 in said cylinder is elevated by such pressure to open said valve h^2 to admit the increased pressure of air from reservoir H in tube 75 A ahead of the carrier. A further advancement of the latter causes the piston h^7 in cylinder h^9 for reservoir H to rise to close its valve h^3 and cut off the escape of air from reservoir H, at the same time the piston h^6 of cylinder h^8 for reservoir H' is raised to open valve h^2 for reservoir H' to admit the further increased pressure of air in reservoir H' to tube A. A further movement of the carrier closes valve h^3 for reservoir H' to cut off the escape of air therefrom, after which the operation is as before described, except that as soon as the carrier is withdrawn from the tube A the pistons in the cylinders h^8 h^9 and levers h^4 h^5 return to their normal positions to open and close the valves h^2 h^3 , respectively, for the reservoirs H H'. 90

The pressure of the levers h^4 h^5 on the pistons h^6 h^7 may be varied, as desired, by adjusting the weights on said levers. In all cases, however, the weight on lever h^5 for piston h^7 of cylinder h^9 for the valve h^3 for reservoir H will be adjusted to an equal or nearly equal pressure as that of lever h^4 of cylinder piston h^6 for valve h^2 for reservoir H', so that the one valve h^3 for reservoir H will close at or nearly at the same time that the other valve h^2 for reservoir H' is opened, in order to cut off the air-supply from reservoir H before the supply in reservoir H' is admitted to tube A. 105

As it is evident that the foregoing novel 110 features may be greatly varied without departing from the spirit of my invention, I do not confine myself to the same as shown and described.

What I claim is—

1. In a pneumatic dispatch-tube system, the combination of a carrier-receiving tube, air-supplies of different pressure having connection with said tube, and devices for successively admitting such air-pressures to the receiver-tube, substantially as set forth.

2. In a pneumatic dispatch-tube system, a carrier-receiver tube A, having movable valve or gate B, reservoir E, having pipe-connection e with valve e' , actuating devices for valves B and e' , and pipe-connection G for tube A between the valve B and the opposite end of tube A, substantially as set forth.

3. In a pneumatic dispatch-tube system, the combination, with a carrier-receiver tube, different supplies of air having different pressures, pipe-connections with cut-offs or valves between said receiver-tube and air-supplies, and devices under the control of the carrier

for successively admitting to the receiver-tube in advance of the carrier such supplies of air, substantially as set forth.

4. In combination with a pneumatic dispatch-receiver tube A, a compressed-air reservoir E, having a pipe-connection with tube A, a valve in said pipe-connection, and electrically-controlled actuating devices in engagement with said valve and under the control of a traveling carrier in tube A for opening and closing said valve, substantially as and for the purpose set forth.

5. In combination with a pneumatic dispatch-tube, a compressed air-reservoir E, having a pipe-connection with said tube, a valve in pipe-connection, electrical devices in engagement with said valve and under the control of a moving carrier in tube A for opening said valve, and air-pressure devices in engagement with said valve and under control of said carrier for closing said valve, substantially as set forth.

6. The combination of tube A, reservoirs E H H', having different air-pressure supplies, pipe-connections with valves between said reservoirs and tube, and actuating devices for said valves under the control of a moving carrier for successively opening and closing said valves, substantially as set forth.

7. The combination of pipe or tube A, gate or valve B, locking device for holding said gate out of the path of said tube A, reservoir E, having pipe-connection e with valve e', and actuating devices for said valves B and e' under control of a moving carrier in tube A, substantially as set forth.

8. The combination of tube A, having branch G and movable section a, reservoir E, having pipe-connection e with valve e', gate or valve B, and actuating devices for valves B and e' under control of a moving carrier in tube A, substantially as set forth.

9. In a pneumatic dispatch-tube system, the combination of a receiver-tube, supplies of air having different pressures in connection with said tube, devices for successively admitting such air-supplies to the receiver-tube in advance of the carrier, and a pipe-connection on said receiver-tube for conducting a part of such pressure to the rear of the carrier, substantially as set forth.

In testimony whereof I affix my signature in presence of two witnesses.
